APPARATUS FOR OBTAINING ETCHABLE DEPOSITS ON PRINTING CYLINDERS

Arnold August Egli, Zurich, Switzerland, and Carl Bökenkamp, Hamburg, Germany, assignors to Langbein - Pfanhauser - Werke Aktiengesellschaft, Leipzig, Germany

Application February 21, 1938, Serial No. 191,760
In Switzerland February 22, 1937

11 Claims. (Cl. 204—217)

It is known in galvanotechnics to use smooth work pieces in the coppering of cylinders or tubes, which prevent the formation of blisters on galvanic deposition and yield with certainty a substantially plane surface of deposited copper. Also a certain density and hardness of the deposited metal is obtained by the smooth work pieces. However a polishing action or the obtainment of a completely smooth homogeneous surface as is necessary e. g. for etchable printing cylinders cannot be achieved. In order to make the copper surfaces of the cylinders etchable these must always be submitted to a special polishing process.

It has now been found that with the help of smooth rollers, etchable galvanic copper deposits can be obtained if certain technical conditions which form the object of the invention are maintained.

According to the invention an agate roller fed to and fro, rolls on the rotating cylinder in such a manner that its position and direction can adjust themselves freely and automatically. Hereby a free rolling, as frictionless as possible, is afforded and any slipping, drawing or pushing of the agate roller on the cylinder surface is avoided. Moreover, according to the invention the roller is increasingly loaded during the electroplating. By this treatment a copper deposit is obtained which after removal of the cylinder from the bath needs only rubbing dry with a rag or paper, to be immediately etchable. Any grinding or polishing is superfluous which is of special advantage in printing cylinders of which the surface layer serving for etching is only so strong that it suffices for the time being for one etching and after the finish or printing is removed as a copper skin or turned down. Further characteristics of the process and the apparatus serving to carry it out are given by the following description of one example of carrying the invention into effect.

Figure 1 is a perpendicular section through a galvanic bath and shows an apparatus formed according to the invention in two positions.

Figure 2 is a plan view of Figure 1 in which the weight carrying arm is broken away.

Figure 3 shows a smoothing roller with its holder in elevation.

Figure 4 is a side view, and

Figure 5 a front view of Figure 3.

In the trough 1 are arranged the anode holders 2 with the anodes 3 while the cylinder to be coppered 4, dips partly into the bath as cathode and is rotated in the direction of the arrow 55

5 (Fig. 1). The screw shaft 5 is regulably driven by means not shown, and turns alternately to the right and left. Correspondingly the slide 6 carried by the shaft 5 is slowly moved to and fro with the nuts 7.

The speed of rotation of the cylinder 4 and the displacement of the slide on the spindle 5 are preferably so correlated that with one revolution of the cylinder the sideways displacement of the smoothing roller will amount to about a third of the width of the path of contact of the roller with the cylinder, so that in traveling a helical path over the surface of the cylinder the edges of the path of contact will overlap.

On the arm 8 of the slide 6 a double bearing 9 is fitted rotatable about the bolt 10. At the end of the arm 8 is a bolt 11 to take up the pierced weight plates 12. In the double bearing 9 is a rotatable spindle 13 which is displaceable in the axial direction and may be held by the collars 14 in order to be able continuously to adjust the smoothing roller 16 to be vertically above the cylinder 4. So that the axis of the spindle 13 serving for adjustment may form a tangent as far as possible to the smoothing roller 16 the bearing fork 15 is correspondingly bent. Thereby a tilting movement produced by the feeding forward of the spindle is avoided.

The displacement of the slide 6 causes the roller 16 to roll in a screw-line on the cylinder. If the axis of the roller were to be, as in the known processes, parallel to the axis of the cylinder, it would have an angle to its line of motion and the roller could not roll without slipping. By the movability in all directions of the roller provided according to the invention this adjusts itself however automatically in the very direction of its rolling, and also even for the change of direction at the two ends of the cylinder, and also for cylinders of different diameter. Larger cylinders produce merely for the same displacement of the slide 6 a smaller angle of inclination than small cylinders. In order that the roller 16 may also accurately adjust itself automatically at the cylinder ends the shaft 13 is capable of rocking about the bolt 10 of the double bearing 9. Moreover the roller 16 must be capable of automatic adjustment on the cylinder so that especially on reversal, slipping is avoided.

By these two possibilities of adjustment a rolling free from slip is afforded. Hindrances to free rotation which otherwise produce a vibration of the roller and a hammered effect on the copper can no longer occur. By a tube 17 and

a sponge 18 bath liquid is supplied directly behind the roller 16 which flows from the roller on to the cylinder. The occurrence of a dry space behind the roller, which would favor oxidation and stripe formation, is thus avoided.

The diameter of the roller decreases from that of the cylindrical middle part about 3 cm. wide, towards both side faces in a curve, as is obvious from Figures 3 to 5. The stationary stones 19 which act on both ends of the cylinder, serve to prevent blister formation at the edges of the cylinder and to smooth these edges.

The process is according to the invention, by the use of the apparatus shown as example, carried out as follows:

At the beginning of the galvanic copper deposition on the cylinder, the agate roller is allowed to roll without additional pressure on the cylinder surface. After about one third of the time necessary to form an etchable layer has passed the roller is loaded by adding weights of about 10 kg. About half an hour before the ending of the coppering the current density is reduced by half. After the conclusion of the coppering the current is wholly switched off, but the cylinder submitted to a further treatment with the considerably higher loaded roller (20-30 kg.). Thereupon, before the cylinder is removed from the bath, the current is switched on for a short time in the reversed direction in order that non-adhering copper particles may be dissolved. Finally the cylinder is washed with warm water, and rubbed down with paper or rag whereupon it is ready for etching.

We declare that what we claim is:

1. An apparatus for electroplating etchable deposits upon a rotating cylindrical base, comprising a slide and mechanism to reciprocate said slide uniformly to and fro in a direction parallel to the axis of said base, an idle roller journaled in said slide about an axis substantially parallel to the axis of and above said base so as to roll uniformly over the deposit on said base, means attaching said roller to said slide so as to be freely bodily shiftable with respect to said slide during reciprocation thereof about an axis perpendicular to the common tangential plane of the base and roller and spaced from the point of tangency, whereby said roller can freely roll over said base in reversed helical paths without sliding as the result of the rotation of said base and the reciprocation of said slide.

2. An electroplating apparatus including a rotating cylindrical base, a roller having a cylindrical central portion terminating in curved end portions of gradually decreasing diameter journaled for free rotation about an axis parallel to or approximately parallel to the axis of rotation of said base, means to reciprocate said roller to and fro endwise of its axis of rotation above said base, means permitting movement of said roller away from the axis of said base as the base diameter changes and a pivoted connection between said last-mentioned means and said roller wherein the pivot has an axis substantially perpendicular to the common tangential plane of the roller and base and spaced from the point of tangency permitting free shifting of the roller axis upon rotation of said base and reciprocation of said roller so that the roller will automatically roll over the base in helical paths without sliding.

3. An electroplating apparatus including a rotating cylindrical base, an idle roller journaled above said cylindrical base for rotation about an axis substantially parallel to that of the cylinder

cylindrical base so as to roll over the deposit as it is plated thereon, a slide, means to reciprocate said slide endwise of said base, and mechanism connecting said roller to said slide, said mechanism including a first pivoted connection having its axis substantially perpendicular to the common tangential plane of the base and roller and substantially spaced from the point of tangency, and a second pivoted connection having its axis lying substantially parallel to said common tangential plane, substantially intersecting the axis of said first pivoted connection, and substantially perpendicular to the axis of said roller.

4. An apparatus as claimed in claim 3 in which said roller comprises a cylindrical central portion terminating in end portions of smaller diameter curving slightly inwardly from said central portion towards the ends of the roller.

5. An apparatus for producing etchable deposits upon a rotating cylindrical base, comprising an idle roller journaled above said base for rotation about an axis substantially parallel to the axis of the base so as to roll over and exert pressure on the deposit as it is plated thereon, said roller having a cylindrical center portion and gradually tapered ends, means to permit variation of the pressure exerted by said roller, and mechanism movable parallel to the length of the cylinder to pull said roller freely over said base on helical paths without relative sliding of the roller with respect to the base, including a pivotal mounting for said roller rotatable about an axis substantially perpendicular to the common tangential plane of the roller and cylinder and spaced from the point of tangency.

6. An apparatus for producing etchable deposits upon a rotating cylindrical base, comprising means to smooth the end edges of the deposit upon said base, an idle roller journaled above said base for rotation about an axis substantially parallel to that of the base so as to roll over said base and exert pressure on the deposit between said edges as it is plated thereon and mechanism to move said roller freely over said base in helical paths from end to end without relative sliding of the roller with respect to the base, including means permitting pivotal movement of the roller about an axis substantially perpendicular to the common tangential plane of the roller and base and spaced from the point of tangency.

7. An apparatus for electroplating deposits upon a cylindrical base rotating about a horizontal axis, comprising a slide and mechanism to reciprocate said slide to and fro in a direction parallel to the axis of said base, an idle roller journaled on an axis substantially parallel to the axis of the base for rolling on said cylindrical base, and means pivotally attaching said roller to said slide so as to swing freely about an axis substantially perpendicular to the common tangential plane of the roller and cylindrical base and substantially spaced from the point of tangency, whereby said roller will track upon said base without sliding.

8. An apparatus for electroplating deposits upon a base having a continuous surface rotating about a horizontal axis, comprising a slide and means to reciprocate said slide to and fro along a line parallel to the surface of the base, an idle roller journaled on an axis substantially parallel to the axis of the base, for rolling on said surface, means permitting movement of said roller away from the axis of the cylinder, and means pivotally attaching said roller to said slide

so as to swing freely about an axis substantially perpendicular to the common tangential plane of the roller and surface and spaced from the point of tangency, whereby said roller will track upon said surface without sliding.

9. An apparatus for electroplating deposits upon a base having a continuous surface rotating about a horizontal axis, comprising a slide and means to reciprocate said slide to and fro along a line parallel to the surface of said base; a substantially horizontally journalled idle roller riding on said surface; a connection pivotally attaching said roller to said slide so as to swing freely about an axis substantially spaced from the point of tangency and substantially perpendicular to the common tangential plane of the roller and surface; said connection including means permitting said roller to pivot about an axis lying substantially in said tangential plane and perpendicular to the roller axis.

10. An apparatus for producing etchable deposits upon a rotating cylindrical base, com-

prising a roller journalled above said base for free rotation about an axis substantially parallel to the axis of said base so as to roll over and exert pressure on the deposit as it is plated thereon, mechanism movable parallel to the length of the base, and means connecting said mechanism and roller to pull said roller freely over the base on helical paths without relative sliding of the roller with respect to the base, including a connection pivotable about an axis substantially perpendicular to the common tangential plane of the roller and base and spaced from the point of tangency.

11. An apparatus as claimed in claim 9 in which said roller comprises a cylindrical central portion terminating in end portions of smaller diameter curving slightly inwardly from said central portion towards the ends of the roller.
